UNITED STATES PATENT OFFICE.

ADOLPH O. NIEDNER, OF MALDEN, MASSACHUSETTS.

CLEANING ATTACHMENT FOR FIREARMS.

1,133,571.

Specification of Letters Patent.

Patented Mar. 30, 1915.

Application filed November 20, 1914. Serial No. 873,214.

To all whom it may concern:

Be it known that I, ADOLPH O. NIEDNER, of Malden, in the county of Middlesex and State of Massachusetts, have invented a new and useful Cleaning Attachment for Firearms, of which the following is a specification.

My invention relates to devices for use in cleaning the bores of the barrels of firearms and especially the barrels of bolt-operated firearms.

An attempt to clean the bore of the barrel from the muzzle end is very likely to seriously harm said interior and especially the rifling while before my invention any attempt to clean from the chamber end of the barrel in bolt-operated firearms has been very difficult because of the fact that the bore is quite inaccessible and the swab or cleaning-material can not be held so as to be properly engaged by the cleaning-rod with the result that the swab slips out of position and is not carried into the barrel by the cleaning-rod except possibly after repeated and painstaking efforts.

My invention is a device for overcoming these objections and consists in a member which guides the swab to the bore of the barrel and which has an entrance readily accessible for insertion of the swab and cleaning rod in proper relative position.

A feature of said member is its construction adapting it for use with standard types of bolt-operated rifles and another feature is the means for holding it in place while in use.

Other invention features will be pointed out below.

In the drawings: Figure 1 is a longitudinal section illustrating my attachment in a firearm of the bolt operated type, the firearm being broken away and partly illustrated in dotted lines; Fig. 2 is a plan of the structure of Fig. 1 with the exception of the portion in dotted lines; and Fig. 3 illustrates the attachment by itself.

I have illustrated my attachment in use in a bolt-operated Springfield rifle although, of course, it may be used with many other types of firearm. Barrel A has bore a , cartridge chamber a' , ramp a^2 , and receiver housing a^3 which serves as an inner bearing for the ordinary bolt. B is the outer bearing for said bolt and has the ordinary interior cylindrical portion.

D represents my tubular guide, one end of

which is preferably beveled at d and is held in alinement with said bore and in adjacency to the breech end of said bore, said end extending preferably to said bore but in any case so near as to insure proper passage of the cleaning rod E and swab F from guide D to bore a . The other end d' of said guide is so far exposed with relation to portion a^3 as to be readily accessible for positioning the swab F and I prefer to locate said d' substantially flush with the outer edge of bearing B. Guide D has an enlarged cylindrical portion d^2 to fit within bearing B.

In using my attachment the bolt is removed and guide D is inserted until end d is adjacent to the bore of the barrel and then end d' is readily accessible for positioning cleaning swab F and cleaning rod E. While the guide is being inserted lugs d^3 and d^4 are in a vertical position so that lug d^3 may pass through bearing B as can be done with the ordinary type of said bearing. When fully inserted the guide may be rotated by knob d^5 until the lugs d^3 and d^4 are in a horizontal position, the portion B serving as a bearing for portion d^2 . In this horizontal position lugs d^3 and d^4 are adapted to engage bearing B very much as the locking means on the ordinary bolt engage said bearing, lug d^3 being adapted to hold guide D locked against outward movement and lug d^4 holding it against inward movement.

It will be observed that the bore of the guide rod is of substantially the same diameter as the bore of the barrel but it might be of slightly different diameter and in either case the swab will pass freely back and forth from the guide to the barrel and back and forth in the barrel, any suitable head on the cleaning rod being used.

What I claim is:

1. A cleaning attachment for firearms of the bolt-operated type consisting of a tubular member adapted to be inserted within the receiver in alinement with the breech end of the bore of the barrel and to guide the cleaning rod and swab to and from the latter and provided with means to coöperate with the outer bolt-bearing for holding said tubular member in place while in use.

2. A cleaning attachment for firearms consisting of a tubular member adapted to be inserted within the receiver in alinement with the breech end of the bore of the barrel and to guide the cleaning rod and swab to

- and from the latter, said member having means adapted by rotative movement of said member to interlock with the receiver to hold said member in place while in use.
- 5 3. A device for use in cleaning the bore of a bolt-operated rifle comprising a removable member with a tubular bore, one portion of said member being exteriorly cylindrical to engage the outer bearing for the bolt member, and said member having locking means to engage the outer bearing for said bolt and thereby hold one end of said member in adjacency to the bore of the rifle and the other end in a readily accessible position.
- 10

4. A cleaning attachment for firearms consisting of a tubular guide having a cylindrical portion to fit the outer bearing for the bolt member and having a lug to engage said bearing to prevent outward movement of said guide, and having another lug with a knob to serve the double purpose of means to prevent inward movement of the guide and to rotate the guide into and out of locked position.

ADOLPH O. NIEDNER.
